COMBINED SQUARE AND PROTRACTOR

Phillip Graham, 2825 Glenmore Ave., Pittsburgh, Pa.

Filed Apr. 16, 1959, Ser. No. 55,545

Term of patent 14 years

(Cl. D52—6)

Fig. 1 is a plan view of a combined square and protractor, showing my new design.

Figure 2 is a sectional view taken along line 2—2 of Figure 1;

Figure 3 is a sectional view taken along line 3—3 of Figure 1.

Fig. 4 is a sectional view thereof taken along line 4—4 of Fig. 1;

Fig. 5 is a sectional view thereof taken along line 5—5 of Fig. 1;

Fig. 6 is a sectional view thereof taken along line 6—6 of Fig. 1;

Fig. 7 is an edge view of the square portion taken from the right of Fig. 1; and

Fig. 8 is a sectional view thereof taken along line 8—8 of Fig. 1.

I claim:

The ornamental design for a combined square and protractor, substantially as shown.
